UNITED STATES PATENT OFFICE.

HARRY M. HAMRICK, OF PHILADELPHIA, PENNSYLVANIA, ASSIGNOR TO THE INTERNATIONAL INCANDESCENT LIGHT COMPANY, OF WEST VIRGINIA.

BURNER.

SPECIFICATION forming part of Letters Patent No. 629,357, dated July 25, 1899.

Application filed March 4, 1899. Serial No. 707,703. (No model.)

To all whom it may concern:

Be it known that I, HARRY M. HAMRICK, a citizen of the United States, residing in the city and county of Philadelphia, State of Pennsylvania, have invented a new and useful Improvement in Burners, which improvement is fully set forth in the following specification and accompanying drawings.

My invention relates to burners which are adapted to be used in connection with gasolene or other hydrocarbon; and it consists more especially of a novel manner of locating and supporting the reservoir for the hydrocarbon and also the compressed-air reservoir adjacent thereto, said reservoirs being supported upon the globe of the lamp at a point near or above the burner thereof, whereby it will be apparent that the hydrocarbon can flow to the burner by the force of gravity, which latter is augmented by the pressure of the compressed air in the adjacent reservoir.

To the above ends my invention consists of an improved construction of compressed-air and hydrocarbon reservoirs which are preferably arranged above the lamp and supported upon the globe thereof, the compressed-air reservoir being suitably connected to the hydrocarbon-reservoir and the latter to the burner.

It further consists of novel details of construction, all as will be hereinafter fully set forth, and particularly pointed out in the claims.

Figure 1 represents a perspective view of a burner, showing the compressed-air and hydrocarbon reservoirs embodying my invention and also a portion of a lamp and globe to which the same are applicable. Fig. 2 represents, on an enlarged scale, a section on line xx , Fig. 1. Fig. 3 represents a section on line yy , Fig. 2.

Similar letters of reference indicate corresponding parts in the figures.

Referring to the drawings, A designates a burner, the same being preferably constructed in accordance with prior patents granted to me, although it is evident that any other suitable form of gasolene or hydrocarbon burner may be employed, and therefore a further de-

tailed description of the burner is unnecessary, since the same forms *per se* no part of the present invention.

B designates a supply-pipe provided with a valve C, which leads from the burner to the hydrocarbon-reservoir D, which latter is filled through a suitable inlet E.

F designates a reservoir for compressed air, the same consisting of the members or compartments G, H, and J, which are preferably arranged so that their casing forms a continuity of the casing of the hydrocarbon-reservoir D, which latter is separated from the portions G and J of the compressed-air reservoir by means of the partitions K.

L designates a connection leading from the compressed-air reservoir to the upper portion of the hydrocarbon-reservoir D, the compressed air being introduced into the reservoir F through the opening M, which is provided with a suitable closure. The pipe L can be provided with a suitable valve, if desired, whereby the flow of compressed air into the hydrocarbon-reservoir D can be regulated according to requirements.

In practice I support the casing in which are contained the reservoirs for compressed air and hydrocarbon upon the upper portion of the lamp-frame N, wherefrom it will be apparent that the hydrocarbon in addition to being fed by gravity will also be subjected to air-pressure upon the top thereof, whereby it will always be subjected to a positive pressure sufficient to force it through the conduit B downwardly to the burner A.

The operation is as follows: The reservoir D is filled with hydrocarbon to the desired extent, the valve C being closed, after which the chambers G, H, and J are filled with compressed air through the opening M. Upon properly manipulating the valve C it will be apparent that the hydrocarbon will be directed to the burner A in the desired quantity, and by proportioning the size of the hydrocarbon-reservoir D and the compressed-air reservoir F it will be apparent that I can charge the reservoirs at each filling so that the light will burn for a predetermined period, which is advantageous when it is de-

sired to use the lighting apparatus in districts where it is intended that the apparatus should burn for only a predetermined period.

By arranging the hydrocarbon and compressed-air reservoirs in the manner described it will be apparent that the same can be readily applied to existing lamps or burners without necessitating any change therein, and the same, furthermore, do not detract from the general appearance or symmetry of the lamp.

The reservoir can be placed upon lamp-globes which are round, oval, or any other similar contour, as is evident.

15 If desired, I may connect the pipe P with the compressed-air inlet M, said pipe extending downwardly within the lamp-globe and being continued through the lamp-post to a point near the base of the latter, whereby the air-pump or compressed-air supply can be readily attached thereto.

It will be apparent that slight changes may be made in the manner of supporting and equipping lamps with hydrocarbon and compressed-air reservoirs constructed as described, and I therefore reserve to myself the right to make all such changes as come within the scope of my invention.

In practice I prefer to employ the pipe P, which is attached to the nipple M and may extend downwardly to the lamp-post for connection for a pump at the base of said post, whereby the air-pump can be readily connected at the lower portion of said post, as is evident.

Having thus described my invention, what I claim as new, and desire to secure by Letters Patent, is—

1. The combination of a lamp-frame, a casing supported upon the latter and divided so as to form reservoirs for compressed air and hydrocarbon respectively, a communication between said reservoirs, a burner supported below said hydrocarbon-reservoir and a conduit leading from said hydrocarbon-reservoir to said burner.

2. The combination of a burner, a globe surrounding the same, reservoirs for compressed air and hydrocarbon supported upon said globe so as to form a continuation of each other, said compressed-air reservoir being separated from the hydrocarbon-reservoir by partitions, a communication between the upper portion of the compressed-air reservoir and said hydrocarbon-reservoir, and a 55 valved conduit leading from the latter to the burner.

3. The combination of a compressed-air reservoir, a hydrocarbon-reservoir D forming a continuation of said compressed-air reservoir and separated therefrom by the partitions K, an inlet leading from said compressed-air reservoir to the upper portion of the hydrocarbon-reservoir, inlets for supplying compressed air and hydrocarbon to said reservoirs respectively, a burner located within the lamp-frame below said reservoirs, and a valved conduit leading from the hydrocarbon-reservoir to said burner.

4. A lamp-frame, a casing surrounding the same and divided interiorly so as to form communicative reservoirs for compressed air and hydrocarbon, a burner supported below said casing, and a valved conduit leading from the hydrocarbon-reservoir to said burner.

5. The combination of a post, a lamp-frame, a casing supported thereon and adapted to surround the same, said casing being divided interiorly so as to form communicating reservoirs for compressed air and hydrocarbon, a burner supported below said casing, a conduit leading from said hydrocarbon-reservoir downwardly to said burner, and an air-supply pipe leading downwardly from said compressed-air reservoir through said post for 85 the purpose of replenishing said latter reservoir.

HARRY M. HAMRICK.
